UNITED STATES PATENT OFFICE.

ISAAC VAN KURAN, OF OMAHA, NEBRASKA.

IMPROVEMENT IN NUT-LOCKS.

Specification forming part of Letters Patent No. **178,090**, dated May 30, 1876; application filed April 18, 1876.

To all whom it may concern:

Be it known that I, ISAAC VAN KURAN, of Omaha, Douglas county, Nebraska, have invented a new and Improved Nut-Lock, of which the following is a specification:

My improved nut-lock consists of a washer of steel over a cavity in the fish-plate, and surrounding the bolt, so that the pressure on the bolt on the fish-plate is transmitted to the surface of the plate surrounding the cavity by the washer, allowing of any required amount of pressure, and at the same time being a spring with sufficient reactionary power against the nut at all times to prevent it from becoming slack, so as to work off or unscrew.

Figure 1 is a side elevation of a rail-joint with my improved nut-lock, and Fig. 2 is a transverse section taken on the line *xx*.

Similar letters of reference indicate corresponding parts.

A is the spring-washer; *B*, the cavity in the fish-plate *C*, over which the washer is arranged; *D*, the nut, and *E* the bolt.

The spring-washer is of plain flat steel, and the cavity is a little larger than the nut. It may be pressed in the plate, or formed by a drill, or countersunk.

I am aware that a spring-plate has been heretofore placed between a recessed block and nut of the fish-plate; but I dispense entirely with the recessed block by making a recess directly in the fish-plate, over which is placed my spring, whereby I lessen the expense about seventy-five per cent., and secure a more permanent joint.

What I claim is—

A nut locked to its bolt by a spring-washer, *A*, over the cavity *B* of fish-plate *C*, as and for the purpose specified.

ISAAC VAN KURAN.
